UNITED STATES PATENT OFFICE.

H. C. ROGERS, OF SCRANTON, PENNSYLVANIA.

IMPROVEMENT IN COAL-BREAKERS.

Specification forming part of Letters Patent No. 43,133, dated June 14, 1864.

To all whom it may concern:

Be it known that I, H. C. ROGERS, of Scranton, in the county of Luzerne and State of Pennsylvania, have invented a new and Improved Tooth for Coal-Breakers; and I do hereby declare that the following is a full, clear, and exact description of the same, reference being had to the accompanying drawings, making a part of this specification, in which—

Figure 1 represents a side elevation of my invention. Fig. 2 is a plan or top view of the same.

Similar letters of reference in both views indicate corresponding parts.

To enable those skilled in the art to make and use my invention, I will proceed to describe it with reference to the drawings.

The tooth is designed for that class of rollers known as the "batten rollers," or for coal-breakers in which two toothed rollers running in opposite directions are employed for the purpose of breaking the coal. The main body A of the tooth is formed of the softest wrought-iron. The point a of the tooth consists of a piece of steel which extends down on the edge of the tooth near to the roller, as clearly shown in Fig. 1 of the drawings. In order to insert said steel point, the edge of the tooth is provided with a V-shaped groove, and after the point is inserted it is permanently united with the wrought-iron body b of the tooth by welding. It is then embedded in the sand of the mold for the cast-iron cylinder, having the base of the tooth projecting into the mold about two inches. The molten iron is then poured in and the tooth is thus firmly embedded in the body

of the cylinder. By referring to Fig. 1 of the drawings it will be noticed that in order to make the tooth perfectly firm, it is made wider at the base, in the form of a pyramid. After the teeth are all in place the steel points are properly tempered. The advantages of this tooth over the ordinary cast-iron tooth are manifest. The cast-iron tooth soon wears away at the point and becomes very blunt, and thus rather grinds than breaks the coal, producing a large percentage of waste or "culm," whereas my improved tooth always presents a pick or sharp point, thus cracking the coal with little or no waste, and when embedded in the manner hereinbefore described it remains forever firm and all the grinding of the teeth, as the coal passes through, serves to sharpen and perfect the point by wearing away the softer iron and leaving the hardened steel prominent.

I do not claim, broadly, as my invention so uniting two metals of different hardness that as the soft metal wears away the hard metal is left prominent; but,

Having thus fully described my invention, what I claim as new, and desire to secure by Letters Patent, is—

As a new article of manufacture, the coal-breaker tooth hereinbefore described, consisting of a pyramidal or tapering body, A, of soft metal, to be secured in the roller R by casting, and a point of steel welded in a groove in the front of the wrought-iron body A.

H. C. ROGERS.
